UNITED STATES PATENT OFFICE

LOSSIE E. ANDERSON, OF CHICAGO, ILLINOIS, ASSIGNOR TO STANDARD OIL COMPANY,
OF WHITING, INDIANA, A CORPORATION OF INDIANA

CRATE

Application filed October 21, 1926. Serial No. 143,116.

My invention relates generally to crates for receiving and holding a liquid container, as for example and more particularly a rectangular five gallon lubricating oil can, and more especially to a crate provided as a means for protecting the can in transit and also in storage, and serving as a means for tiltingly supporting the can to permit its contents to be readily poured into a smaller container, as is customary in making use of the oil.

My primary objects are to provide a novel, simple and inexpensive construction of crate adapted more especially for the purposes stated and one which may be made relatively inexpensively and still present the desired strength for protecting the can against damage in shipment and stably pivotally support the can.

Referring to the accompanying drawings:—

Figure 1 is a perspective view of a crate constructed in accordance with my invention and shown as containing a can, the cover portion of the crate being shown in a position in which it is raised out of engagement with the body portion of the crate, the can being shown in the position it assumes when positioned in the crate for transport. Figure 2 is a perspective view of the trunnion-equipped can shown in Fig. 1; and Figure 3, a vertical cross sectional view taken through the upper portion of the structure shown in Fig. 1 at the plane in which the trunnions of the can extend.

The particular illustrated construction of crate, which is of general box-like, rectangular, form, comprises a body portion represented at 10 and a removable cover portion represented at 11, the crate, by preference, being constructed from ordinary wood boards nailed, or otherwise secured, together.

The body portion comprises a bottom board 12 from opposite edges of which side-wall-forming boards 13 and 14 disposed in a rectangular arrangement, upwardly extend, with cleats 15 flatwise opposing the outer surfaces of the boards 13 at the lower ends of the latter, all of the parts described being

firmly secured together, as by means of nails. The boards 14 reach considerably short of the tops of the boards 13, in the construction illustrated only about half way, whereby the crate presents openings at opposed sides thereof through which labels commonly provided on opposed sides of commercial oil cans are exposed to view at all times when the can is positioned in the crate.

The boards 13 carry transversely disposed cleats 16 on their outer sides at their upper edges as shown, these cleats being securely fastened in position as for example by nails, with their opposite ends preferably extending beyond the adjacent edges of the boards carrying them.

In the construction of crate illustrated provision is made for tiltably supporting the can upon the crate so that the can may be tilted thereon to pour the contents therefrom for use. The can, represented at 17, is shown as provided with trunnions 18 soldered, or otherwise secured, to opposite sides of the can, these trunnions being adapted to be rockably seated in upwardly opening recesses 19 formed in the side boards 13 adjacent the upper edges of the latter, in which position the lower edges of the can, in its tilting movements, clears the upper edges of the side boards 14.

When the can is placed in the crate for shipping purposes, it sets down into the crate to the position shown in Fig. 1 in which position its trunnions extend far below the position they occupy when the can is arranged for tilting, and to permit the can to be thus introduced into the crate and raised, when desired, to position it for tilting, the side boards 13 are vertically slotted, as illustrated at 19, with their upper ends open, to receive the trunnions 18 as shown in the drawings.

The cover 11, which is provided primarily for holding the can in the crate during shipment, is shown as formed of a top board section 20 recessed along opposite edges thereof as represented at 21 to provide oppositely-facing shoulders 22 inset from the edges of the board 20, its other edges being provided with depending cleat-like boards 23 rigidly

secured to the board 20. The cover is so constructed, as shown, that when applied to position on the top of the body portion 10, the portion of the board 20 between the shoulders 22 will extend into the space between the side boards 13 and the shoulders 22 will flatwise oppose the inner surfaces of the upper edge portions of these side boards; the portions of the board 20 which extend outwardly beyond the shoulders will overlap the upper edges of the side boards 13 including the cleats 16; and the depending board portions 23 will extend into the spaces between the opposed projecting ends of the cleats 16 and lap the upper edges of the side boards 13.

15 The cover may be releasably held down on the body portion in any suitable way, as for example by tying, or nailing, it in place, it being understood that when the can is to be shifted in the crate to the position in which 20 it is tiltably supported thereon, the cover is first removed.

25 A crate made in accordance with my invention may thus be economically manufactured, it being noted that by providing the cleats 16 comparatively thin side boards may be used in spite of the fact that these boards are weakened by providing the slots 19.

30 The provision of the openings at the upper portions of the side walls through which the labels at the opposite sides of the can are exposed to view, is a desirable feature as thereby the labels at both of these sides of the can are accessible to view at all times, even when the cover 20 is secured in place.

35 The feature of forming the cover of the structure shown and described is also of advantage inasmuch as it may be economically manufactured and when in operative position on the body portion of the crate cooperates therewith to cause the crate to present the desired rigidity and resist stresses, as for example in handling, tending to crush the sides of the crate.

40 45 While I have illustrated and described a particular construction embodying my invention, I do not wish to be understood as intending to limit it thereto as the same may be variously modified and altered without departing from the spirit of the invention.

50 55 What I claim as new, and desire to secure by Letters Patent, is:

A structure of the character described comprising a substantially boxlike crate to receive a can and formed of a body portion and a removable cover opposed side walls of said body portion comprising side-boards, cleats secured to said side-boards adjacent the upper ends of the latter and each extending laterally at its opposite ends beyond said side-boards, said cover extending into the space between said side walls and having inset shoulder portions at opposite edges thereof, said shoulders extending below the upper edges of said side walls and flatwise opposing

the inner surfaces of the latter and the portions of said cover projecting beyond said shoulders overlying the upper edges of said side walls, said cover also comprising depending portions at its other edges which terminate short of the free edges of the last mentioned portions of the cover and extend into the spaces between the extended ends of said cleats and overlap the edges of said side walls.
